Primary Examiner—Marcus A. Jackson*Attorney, Agent, or Firm*—Wells, St. John, Roberts, Gregory & Matkin, P.S.[57] **CLAIM**

The ornamental design of a combined rearview mirror and signalling indicator, as shown and described.

DESCRIPTION

FIG. 1 is a perspective view of a combined rearview mirror and signalling indicator showing my new design with the signalling indicator energized, and with the broken line showing for illustrative purposes only and forming no part of the claimed design;

FIG. 2 is a front elevational view thereof;

FIG. 3 is a rear elevation view of the combined rearview mirror and signalling indicator of FIG. 1;

FIG. 4 is a side elevation view of the combined rearview mirror and signalling indicator of FIG. 1;

FIG. 5 is a side elevation view of the combined rearview mirror and signalling indicator of FIG. 1 as seen from the opposite position as shown in FIG. 4;

FIG. 6 is a top plan view of the combined rearview mirror and signalling indicator of FIG. 1; and,

FIG. 7 is a bottom plan view of the combined rearview mirror and signalling indicator of FIG. 1.
